ANTENNA SYSTEM

William M. Hurst, Douglaston, N. Y., assignor,
by mesne assignments, to Hazeltine Research,
Inc., Chicago, Ill., a corporation of Illinois

Application April 3, 1945, Serial No. 586,348

10 Claims. (Cl. 174—12)

1

The present invention relates to antenna systems and, particularly, to such a system suitable for use with aircraft wherein the antenna system during operation is subjected to variations of atmospheric pressure resulting from the flight of the aircraft between low to high altitudes.

For certain applications, it is desirable to provide on aircraft one or more short, vertical, relatively rigid antennas. It has heretofore been conventional to support such antennas in a position entirely exposed to the weather. This has the disadvantage that the antenna is subjected during flight to mechanical stresses caused by air flow past the antenna. There is the further disadvantage that such exposed antennas become covered with dirt and may become coated with a film of condensation or a layer of ice, all of which conditions, substantially reduce the antenna efficiency. For example, a film of moisture on the antenna accelerates corrosion of the antenna surfaces thus mechanically to weaken the antenna. A deposit of ice on the antenna conductor may seriously change the antenna impedance and thereby impair the desired impedance matching between the antenna, an associated transmission line which couples the antenna to a wave-signal translating apparatus, and the output circuit of a transmitting apparatus or the input circuit of a receiving apparatus. A deposit of ice on the antenna-supporting insulators likewise tends to change the antenna impedance and, additionally, tends to impair the desired insulating qualities of the insulators for high wave-signal potentials. Deposits of dirt on the insulating support members for the antenna may cause substantial losses of wave-signal power.

To avoid these disadvantages of the exposed antenna, it has been proposed that the antenna be enclosed within a housing of insulating material secured to or forming a part of the aircraft structure. The forms of antenna housings heretofore proposed cannot readily be hermetically sealed, to protect the antenna from dirt, moisture and ice, without introducing severe problems which relate largely to the mechanical design of the housing and arise by virtue of the wide range of variations of pressure encountered in the operation of high altitude aircraft. The enclosed type of antenna systems heretofore suggested consequently are so constructed that one or more openings are provided to connect the interior of the housing to the surrounding atmosphere. While this housing protects the antenna itself from mechanical stresses due to air flow past the antenna during flight, the exchange of

2

air between the interior of the housing and the outside atmosphere with pressure and temperature variations causes dirt and moisture to be drawn into the housing where they may readily form an undesirable deposit on the antenna and its insulating support members.

It is an object of the present invention to provide a new and improved antenna system which avoids one or more of the disadvantages and limitations of prior antenna systems of the type described.

It is an additional object of the present invention to provide a new and improved antenna system, particularly suited for use with aircraft, which possesses uniformly high efficiency and a high degree of stability of its electrical characteristics at all usual altitudes and temperatures encountered.

It is a further object of the invention to provide a new and improved antenna system having an antenna conductor enclosed within a protective housing which, while hermetically sealed, has an automatically maintained condition of substantial equilibrium between the pressure within the housing and the surrounding outside atmospheric pressure even with substantial changes of the latter, so that excessive mechanical stresses on the housing due to pressure differential are avoided.

It is an additional object of the invention to provide an antenna system having an antenna enclosed within a hermetically sealed housing filled with a gas which is maintained at a uniformly low percentage of humidity at all times.

In accordance with one form of the invention, an antenna system comprises an antenna, a non-conductive relatively rigid housing enclosing the antenna, and means for hermetically closing the housing and including at least one portion providing a chamber wall exposed to atmospheric pressure and movable in response to variations thereof. The last-mentioned means provides with the housing a hermetically sealed container having a portion of constant volume and a portion of volume variable with atmospheric pressure to reduce the pressure differential between the gas pressure within the housing and the atmospheric pressure without the housing which would otherwise occur with decreases of atmospheric pressure.

For a better understanding of the present invention, together with other and further objects thereof, reference is had to the following description taken in connection with the accompanying

drawing, and its scope will be pointed out in the appended claims.

Referring now to the drawing, the single figure thereof is a sectional elevation illustrating the construction of an antenna system embodying the present invention.

Referring now more particularly to the drawing, there is illustrated an antenna system embodying the present invention in a particular form. This system includes an antenna 10 and a nonconductive relatively rigid housing or envelope 11 enclosing the antenna and hermetically sealed except for an equalizing port 12 in one wall 13 thereof. The housing 11 preferably is of molded plastic, a transparent plastic being preferred to permit the inspection of the interior of the housing without the necessity of opening it up. The interior of the housing 11 has sufficient capacity to provide a substantial air space all the way around the antenna 10 in order that the distributed capacitance of the latter shall be established primarily by the dielectric constant of the gas medium which fills the interior of the housing. The term "gas" as used in the present specification is intended to include the usual inert gases, for example, nitrogen or carbon dioxide, and also to include air. The housing 11 is usually positioned on the exterior surface of an airplane wing or fuselage 16 and is preferably streamlined in cross section to minimize the resistance to the flow of air around its exterior surface.

The antenna system also includes hermetically sealed means, comprising an elastic balloon 14, hermetically sealed to the housing 11 and having an internal chamber 15 connecting with the port 12, in a manner presently to be explained in greater detail, to permit the free passage of gas between the interior of the housing 11 and the chamber 15. Essentially, the last-mentioned means comprises means having at least one movable chamber wall exposed to atmospheric pressure and movable in response to changes thereof to vary the volume of the chamber, thereby to reduce the pressure differential between the gas pressure within the housing 11 and the atmospheric pressure outside it which would otherwise occur with decreases of atmospheric pressure. The balloon 14 is of flexible and especially elastic material, preferably an elastomer, such as one of the buna rubber family, a modified butadiene acrylonitrile copolymer, a chloroprene polymer, or an organic polysulphide. All of these materials are of the artificial rubber type and possess the ability to retain their elastic characteristics at the temperatures prevailing at altitudes of 30,000 to 50,000 feet above sea level.

The antenna 10 is of an elongated form, for example a quarter-wave vertical antenna, and is supported at its ends 17 and 18 by insulating members 19 and 20, respectively, provided at the top and bottom portions of the housing as indicated. A coaxial connector 21 extends from the lower end of the antenna and projects externally through a side wall of a cup-shaped sub-housing 22 to permit the antenna to be coupled through a coaxial transmission line to an external wave-signal apparatus, not shown.

The balloon 14 has a neck 23 which is attached to a nipple 24 provided on one wall of a hollow housing 26 positioned in the sub-housing 22. The latter has an interior chamber 27 connected with the equalizing port 12 through a tube 28. The

housing 26 is filled with a hygroscopic substance 31, such as silica gel, which serves to reduce by absorption the moisture content of the gas filling the interior of the housing 11 and balloon 14.

5 A perforated basket 30 which may be of a plastic material is attached to the sub-housing 22 in any suitable manner to protect the balloon 14. Free access of the atmosphere to the exterior surface of the balloon 14 is provided by perforations in the walls of the basket 30.

A collar 32 surrounds a flared base portion of the housing 11, an insulating ring 33, a gasket 34 provided hermetically to seal the housing 11 and its wall member 13, and the sub-housing member 22. Machine screws 35 maintain the elements last-mentioned in assembled relation as a unitary structure and secure the assembly to the airplane wing or fuselage 16.

Consider now the operation of the antenna system just described. The interior of the housing 11, the interior 27 of the housing 26 and chamber 15 of the balloon 14 are usually filled with gas at normal atmospheric pressure at the time of assembly of the antenna system. When the enclosed gas is air, this simply means that no attempt is made to evacuate the air at the time of assembly. The balloon 14 is preferably collapsed at the time of assembly. After assembly, any internal pressure within the housing 11 exceeding that of the surrounding atmospheric pressure, such as during flight of an airplane to high altitudes, results in an expansion of the gas within the housing 11 to inflate the balloon 14. This expansion of the gas within the system to inflate the balloon 14 is effective to maintain a substantial balance between the air pressures within and without the housing 11 so that no injurious stress will be exerted on the latter. As the gas flows 20 in both directions between the chambers of the housing 11 and balloon 14, it passes through the intervening compartment 27 and thus passes through the silica gel or other hygroscopic substance 31. This substantially dehumidifies the 25 enclosed gas.

The antenna 10 operates in conventional manner to receive or radiate wave signals.

The balloon 14 preferably has a wall thickness limited to about one thirty-second of an inch maximum to minimize the gas or air pressure required to inflate it. This thickness has been empirically established and provides an adequate factor of safety while at the same time affording ample flexibility and elasticity.

55 The use of silica gel treated with cobalt chloride is desirable from the standpoint that the color of the hygroscopic substance 31 varies with the moisture content thereof. Since clear plastic may be used for the housing 26 and sub-housing 22, the indications provided by such coloring can be readily observed at such times as may be desired.

From the above description of the invention, it will be apparent that the balloon 14, the housing 26, and the tube 28 comprise means for hermetically closing the housing 11 and including at least one portion, namely the balloon 14, providing a chamber wall exposed to atmospheric pressure and movable in response to variations thereof. It will further be apparent that the means last-mentioned provides with the housing 11 a hermetically sealed container having a portion, namely the housing 11 and housing 26, of constant volume and a portion, namely the balloon

14. of volume variable with atmospheric pressure to reduce the pressure differential between the gas pressure within the housing 11 and the atmospheric pressure without the housing which would otherwise occur with decreases of atmospheric pressure.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An antenna system comprising, an antenna, a nonconductive relatively rigid housing enclosing said antenna, and means for hermetically closing said housing and including at least one portion providing a chamber wall exposed to atmospheric pressure and movable in response to variations thereof, said means providing with said housing a hermetically sealed container having a portion of constant volume and a portion of volume variable with atmospheric pressure to reduce the pressure differential between the gas pressure within said housing and the atmospheric pressure without said housing which would otherwise occur with decreases of atmospheric pressure.

2. An antenna system comprising, an antenna, a nonconductive relatively rigid housing enclosing said antenna, and means for hermetically closing said housing and including at least one portion providing a chamber wall of flexible construction exposed to atmospheric pressure and movable in response to variations thereof, said means providing with said housing a hermetically sealed container having a portion of constant volume and a portion of volume variable with atmospheric pressure to reduce the pressure differential between the gas pressure within said housing and the atmospheric pressure without said housing which would otherwise occur with decreases of atmospheric pressure.

3. An antenna system comprising, an antenna, a nonconductive relatively rigid housing enclosing said antenna, and means for hermetically closing said housing and including at least one portion providing a chamber wall of elastic material exposed to atmospheric pressure and movable in response to variations thereof, said means providing with said housing a hermetically sealed container having a portion of constant volume and a portion of volume variable with atmospheric pressure to reduce the pressure differential between the gas pressure within said housing and the atmospheric pressure without said housing which would otherwise occur with decreases of atmospheric pressure.

4. An antenna system comprising, an antenna, a nonconductive relatively rigid housing enclosing said antenna, means for hermetically closing said housing and including at least one portion providing a chamber wall exposed to atmospheric pressure and movable in response to variations thereof, said means providing with said housing a hermetically sealed container having a portion of constant volume and a portion of volume variable with atmospheric pressure to reduce the pressure differential between the gas pressure within said housing and the atmospheric pressure without said housing which

would otherwise occur with decreases of atmospheric pressure, and a hygroscopic substance in contact with said gas for reducing the moisture content of the gas filling the interior of said container.

5. An antenna system comprising, an antenna, a nonconductive relatively rigid housing enclosing said antenna and hermetically sealed except for an equalizing port in one wall thereof, and 10 hermetically sealed means hermetically sealed to said housing and including a chamber connecting with said port to permit the free passage of gas between said chamber and the interior of said housing, said means having at least one movable chamber wall exposed to atmospheric pressure and movable in response to changes thereof to vary the volume of said chamber, thereby to reduce the pressure differential between the gas pressure within said housing and the atmospheric pressure without said housing which would otherwise occur with decreases of atmospheric pressure.

6. An antenna system comprising, an antenna, a nonconductive relatively rigid housing enclosing 25 said antenna and hermetically sealed except for an equalizing port in one wall thereof, and hermetically sealed means hermetically sealed to said housing and including a chamber connecting with said port to permit the free passage of gas between said chamber and the interior of said housing, said means having at least one movable chamber wall of flexible material which retains its flexibility at high altitudes and is exposed to atmospheric pressure for flexible movement in response to changes thereof to vary the volume of said chamber, thereby to reduce the pressure differential between the gas pressure within said housing and the atmospheric pressure without said housing which would otherwise occur with decreases of atmospheric pressure.

7. An antenna system comprising, an antenna, a nonconductive relatively rigid housing enclosing 45 said antenna and hermetically sealed except for an equalizing port in one wall thereof, and a hermetically sealed elastic container hermetically sealed to said housing and providing a chamber connecting with said port to permit the free passage of gas between said chamber and the interior 50 of said housing, said container having at least a portion of its exterior surface exposed to atmospheric pressure and elastically movable in response to changes thereof to vary the volume of said chamber, thereby to reduce the pressure differential between the gas pressure within said housing and the atmospheric pressure without said housing which would otherwise occur with decreases of atmospheric pressure.

8. An antenna system comprising, an antenna, a nonconductive relatively rigid housing enclosing 65 said antenna and hermetically sealed except for an equalizing port in one wall thereof, and hermetically sealed means hermetically sealed to said housing and including a chamber connecting with said port to permit the free passage of gas between said chamber and the interior of said housing, said means having at least one movable chamber wall formed of one of the elastomers and exposed to atmospheric pressure for elastic movement in response to changes thereof to vary the volume of said chamber, thereby to reduce the pressure differential between the gas pressure within said housing and the atmospheric pressure without said housing which would other-

wise occur with decreases of atmospheric pressure.

9. An antenna system comprising, an antenna, a nonconductive relatively rigid housing enclosing said antenna and hermetically sealed except for an equalizing port in one wall thereof, and a hermetically sealed container formed of one of the elastomers and hermetically sealed to said housing for providing a chamber connecting with said port to permit the free passage of gas between said chamber and the interior of said housing, said container having at least a portion of its exterior surface exposed to atmospheric pressure and elastically movable in response to changes thereof to vary the volume of said chamber, thereby to reduce the pressure differential between the gas pressure within said housing and the atmospheric pressure without said housing which would otherwise occur with decreases of atmospheric pressure.

10. An antenna system comprising, an antenna, a nonconductive relatively rigid housing enclosing said antenna and hermetically sealed except for an equalizing port in one wall thereof, hermetically sealed means hermetically sealed to said housing and including a chamber connecting with said port to permit the free passage of gas between

5 said chamber and the interior of said housing, said means having at least one movable chamber wall exposed to atmospheric pressure and movable in response to changes thereof to vary the volume of said chamber, thereby to reduce the pressure differential between the gas pressure within said housing and the atmospheric pressure without said housing which would otherwise occur with decreases of atmospheric pressure, and a 10 hygroscopic substance located between the interior of said housing and said chamber in the path of gas passing therebetween for reducing the moisture content of the gas filling the interior of said housing.
